UNITED STATES PATENT OFFICE.

WINFIELD L. DINSMOOR, OF SAN FRANCISCO, CALIFORNIA.

CARD-FILE.

1,340,757.

Specification of Letters Patent. Patented May 18, 1920.

Application filed July 30, 1919. Serial No. 314,194.

To all whom it may concern:

Be it known that I, WINFIELD L. DINSMOOR, a citizen of the United States, and a resident of San Francisco, in the county of 5 San Francisco and State of California, have invented a new and Improved Card-File, of which the following is a description.

My invention relates to filing devices of the type in which spindles are employed 10 to receive articles to be filed, and more particularly the invention has in view to produce a file employing index cards on the spindles and so arranged as to provide a convenient means for keeping a file of business cards, such as the cards of patrons collected by business men, or the cards of the 15 patients or clients of professional men. My improved file, however, is adapted for other purposes, as for example, to hold calendar 20 cards. The invention applies particularly to a file having fixed and relatively movable spindles adapted to be juxtaposed at their upper ends and thus form arch members, or separated for the filing or removal 25 of cards or the like. The invention resides in the novel means for moving and controlling the movable spindles.

Reference is to be had to the accompanying drawings forming a part of this specification, it being understood that the drawings are merely illustrative of one example 30 of the invention.

Figure 1 is a perspective view of a file embodying my invention;

Fig. 2 is a longitudinal vertical section on the line 2—2, Fig. 3;

Fig. 3 is an inverted plan view with parts broken away and others partly in section;

Fig. 4 is a transverse vertical section on 10 the line 4—4, Fig. 3;

Fig. 5 is a detail in transverse vertical section of a punch employed for punching the cards; the section being taken on the line 5—5, Fig. 4.

15 In carrying out my invention I provide a suitable base 10 constituting a table, and which is elevated by suitable means, there being shown for the purpose depending end flanges 11 to the lower ends of which tubular rubber cushions 12 are applied that the base may not mar a desk top, for example. The table is adapted to support a series of index cards 13 having tabs as usual bearing in practice suitable symbols according 20 to the character of the cards to be filed between the index cards. The index cards 13

are perforated at one end to receive arched filing spindles composed of fixed spindles 14 and relatively movable spindles 15, the upper ends of the respective spindles lying in 60 close relation when brought together to form a continuous arched filing device.

The movable spindles 15 extend downwardly through parallel longitudinal slots 18 in the table and are secured to a slide 65 plate 16 by nuts 17 or other suitable means. The fixed spindles 14 pass through holes for the purpose in the plate in the table 10 and through a bar washer 19 and receive nuts 20 or the like, the bar washer being spaced 70 from the under side of the table 10 by small washers 21 on each spindle 14, thereby producing a guiding space for an arm 22 which extends from the slide plate 16 at one end thereof. From the opposite end of the slide 75 16 a guide arm 23 extends into a slot 24 in the adjacent depending flange 11. At a side of the slide 16 is an operating handle arm 25, the outer end 26 of which is bent downwardly. Thus, by grasping the handle arm 80 25, the slide 16 may be moved to separate the spindles 15 from the spindles 14 as indicated in dotted lines in Fig. 2, the arm 23 passing through the opening 24. I provide spring means to return the slide after a 85 separating movement of the spindles and latch means to hold the slide in position with the spindles thus separated. The latch 27 lies at the under side of the slide 16 and is pivoted near one end thereto by a screw 90 28 or the like, to swing laterally. In a side of the latch 27 is a notch 29 which, when the slide 16 is moved to separate the spindles, is adapted to engage the flange 11 at 95 an end of the opening 24. A retractile 100 spring 30 is connected with the slide through the medium of the latch 27, said spring at one end engaging in a notch 31^a on a lateral arm 31 of the latch, the spring being secured at its opposite end to any fixed 105 part of the base as at 32. The latch extends at its outer end into the opening 24 at all times so that the spring 30 can only swing the latch to the extent permitted by the notch 29 when the latter is brought into 110 register with the flange 11 at the opening 24 and therefore the spring has both a tendency to swing the latch into the latching position and to retract the slide 16 after an outward movement of the latter. A lever 110 arm 33 extends from the latch 27 at the opposite side from the spring 30. The said

lever arm lies beneath the handle arm 25 of the slide so that both may be grasped at once.

It will be clear that when the slide is moved by its handle 25, the latch 27 is carried outwardly also and the spring 30 thus placed under tension. When the notch 29 of the latch arrives at the adjacent flange 11, the tension of the spring swings the latch 27 into latching position so that the slide is held in the outer position with the spindles 15 thus maintained separated from the spindles 14. To permit the spring 30 to retract the slide the handle 25 and the lever arm 33 are grasped, thereby rocking the latch 27 to disengage the same and permit the spring to return the slide.

With the described file any desired number of index cards with the articles to be filed therebetween may be moved upwardly on the spindles 14 and downwardly onto the spindles 15, so that upon the separation of the spindles by movement of the slide 16, any desired business card or calendar card or the like between the business cards may be removed, or additional business cards or calendar cards may be placed on the spindle in proper locations between the index cards. The file is particularly intended for filing business cards which are punched to correspond with the index cards 13 to thereby be passed onto the spindles or removed therefrom. In order to punch the business cards I provide a punch 34 mounted on the table 10 at a side thereof. The punch preferably involves two parallel spring-pressed punches 35 that may be depressed by the head 36, the said punches being in vertical alinement with holes 37 in the die 38 in the base of the punch. The punch is suitably mounted on the table 10 which has holes 39 registering with the holes 37 for the escape of the punched material to the under side of the base. A screw 40 is shown as one means for securing the punch to the table. The entrance slot 41 in the punch to receive a business card, for example, to be punched, is disposed laterally outward at a side of the table 10 so that the card can thus be conveniently passed into the punch. Thus, by mounting the punch on the table and disposing the entrance slot 41 thereof laterally outward at a side of the table, the punch is always conveniently available to punch business cards as they are collected to permit them to be properly filed and preserved for reference.

I would state in conclusion that while the illustrated example constitutes a practical embodiment of my invention, I do not limit myself strictly to the mechanical details

herein illustrated, since manifestly the same can be considerably varied without departure from the spirit of the invention as defined in the appended claims.

65

Having thus described my invention, I claim as new, and desire to secure by Letters Patent:

1. A file of the class described including a support, a filing arch thereon composed of a fixed spindle and a relatively movable spindle, a slide on said support carrying the movable spindle, a pivoted latch carried on said slide and adapted to engage the support to hold the slide with the spindles separated, and a spring connected with said latch to retract the slide by exerting its force on the latch, said spring tending to swing the latch in a direction to effect engagement with the support.

80

2. A filing device including a base, a filing arch formed of a fixed and relatively movable spindle, a slide carrying the movable spindle, a handled arm on the slide to move the latter for separating the spindle, a latch carried by the slide and pivoted thereon and adapted to engage a relatively fixed member on the base to hold the slide with the spindles separated, a lever arm on the latch and disposed adjacent to said handled arm for the joint grasping of said lever arm and handled arm, and spring means acting on the latch and tending to throw said latch to the latching position and adapted to return the slide after a separation of the spindles.

85

3. A filing device including a base comprising an elevated table having parallel slots therein, and having a depending member below the table, filing arches consisting of a pair of spindles rising from the table and a second pair of relatively movable spindles extending through the slots of the table to the under side thereof, a slide at the under side of the table and carrying the movable spindles, an arm on said slide at one side, said depending member having an opening through which said arm is adapted to pass when the slide is moved to separate the respective pairs of spindles, a laterally swingable latch carried by the slide and having a notch to engage the depending member of the base at the opening therein, a lateral handle arm on the slide and projecting beyond the table for convenient grasping, a lever arm on the latch and extending beneath said lever and beyond the table, and spring means acting on said latch and tending to throw the same to the latching position.
